UNITED STATES PATENT OFFICE.

JESSE CRITZ KING, OF ST. CATHARINES, ONTARIO, CANADA, ASSIGNOR TO THE WILLSON CARBIDE WORKS COMPANY OF ST. CATHARINES, LIMITED, OF ST. CATHARINES, CANADA, A CORPORATION OF ONTARIO.

ELECTRIC FURNACE.

No. 872,352.

Specification of Letters Patent.

Patented Dec. 3, 1907.

Application filed January 5, 1904. Serial No. 187,837.

To all whom it may concern:

Be it known that I, JESSE CRITZ KING, a citizen of the United States, residing at St. Catharines, in the Province of Ontario, Canada, have invented certain new and useful Improvements in Electric Furnaces, of which the following is a specification.

My invention aims to provide certain improvements in apparatus for electric smelting or other electric furnace treatment, and especially for the manufacture of calcium carbide or other substances which are formed under similar conditions. In the manufacture of calcium carbide, for example, a mixture of lime or limestone and carbon is fed into the furnace and the mixture is fused and converted into calcium carbide, with the well known reactions. In the processes most commonly employed only the central portion 15 of the material is fused and reduced, so that the pig of carbide which is formed is surrounded by a crust of the unreduced or partially reduced mixture of lime and carbon. This crust is practically a waste product, and 20 furthermore the cost of separating it from the pure carbide is very great. This expense, and the public nuisance caused by the odor which a dump pile of the crust makes, are very serious objections to the present 25 methods of manufacture. Likewise according to the most common practice a large part of the mixture outside of the crust in the furnace is unreduced, and has to be disposed of by being carried back and mixed with fresh 30 material, which is a matter of considerable expense and annoyance.

My present invention provides a furnace which can be operated to produce a crustless carbide and to avoid the presence of any substantial quantity of unreduced material. All the material to be utilized in forming the carbide is confined to the zone of fusion, so as to be completely reduced. This is preferably done by passing the material through 45 a die the walls of which closely circumscribe the fused material and which die separates the unreduced material above from the reduced material beneath. The die preferably constitutes one of the electrodes, the other 50 electrode being a pencil arranged with reference to the die so as to provide a space be-

tween the two through which the material may be passed. Preferably the die flares downwardly and the material is fed downwardly through the die. By reason of this 55 construction the congealing outer portion of the pig of carbide is easily separated from the wall of the die as it moves downward.

My invention contemplates the feeding of the material through the zone of fusion by 60 any suitable means, preferably by withdrawing the product as it is reduced so as to allow fresh material to enter the zone of fusion, the rate of withdrawal being controlled either by hand or by automatic regulating means. 65

Various other improvements are referred to in detail hereinafter.

The accompanying drawings illustrate embodiments of the invention.

Figure 1 is a longitudinal section, and 70 Fig. 2 a horizontal section on the line 2—2 of Fig. 1, illustrating one style of furnace; a complete electric circuit being shown in connection with Fig. 1. Figs. 3, 4 and 5 are respectively a longitudinal and a transverse 75 vertical section and a horizontal section on the line 5—5 of Fig. 3 illustrating another style of furnace. Figs. 6 and 7 are vertical sections of other styles of furnaces, the former being a single-arc furnace and the latter a double-arc furnace. 80

Referring to the embodiments shown in the drawings, and especially in Figs. 1 and 2, A is a carbon pencil constituting one of the electrodes, and B are carbon blocks or sections connected with each other and constituting all together the opposite electrode. 85 The inner ends of the carbons B are contiguous to each other, as shown in Fig. 2, so that they form substantially a die surrounding 90 the pencil A. The pencil A is of such size as to leave an annular space C between the opposite electrodes. This space may be rectangular as shown, or otherwise shaped. It is through this annular space, across which 95 the current continually passes, that the material D is passed, and first liquefied into a pool, somewhat as shown at E, which subsequently solidifies into a pig F of carbide or other material, depending on the ingredients 100 used. With carbide, which solidifies at a very high temperature, no cooling means is

ordinarily required, but for products which congeal at lower temperatures the die may be cooled by a water jacket, as shown at *e* in Fig. 3, or otherwise.

5 The current is supplied from a generator *G*, preferably an alternating current generator. Preferably a transformer *H* of any suitable type is interposed between the furnace and the dynamo, and reduces the high 10 voltage between the primary leads *J* and *K* to a low voltage between the secondary terminals and leads *J'* and *K'*. Preferably the feed is controlled by lowering the pig of reduced material at a rate not faster than that 15 at which the furnace can work with the desired efficiency. The several figures of the drawings show suitable arrangements for this purpose. In Fig. 1 the pig is curved, and passes down through a fixed curved 20 chute *L*. Preferably this chute is larger than the pig, as shown, and the casting *M* which carries the carbons forming the electrode *B* is so shaped as to permit the passage of a portion of the material *D* outside of the 25 die formed by the meeting ends of the carbon so that the material is fed about the pig and preferably on all sides of it between the pig and the walls of the chute *L*. Any other suitable nonconducting material may be fed 30 about the pig to prevent injury to the walls of the chute by the high heat and to facilitate the passage of the curved pig through the chute. In Fig. 2 the shape of the casting *M* is indicated, openings *N* permitting the 35 passage of a portion of the material *D* as explained.

A suitable mechanism for drawing out the pig *F* comprises a conveyer made of sections or flights *O* connected together to form a 40 continuous curved platform running on rollers *P* carried by the fixed structure and moved downward by means of a line of teeth *Q* forming a continuous rack which is in engagement with a pinion *R* driven by a 45 worm gear *S* controlled by a hand wheel *T*. The inner face of the sections *O* of the conveyer is substantially in line with the inner face of the wall of the chute *L*. The guide rollers and operating parts of the conveyer 50 are carried by a second chute *U* in the upper open end of which successive sections of the conveyer are added from time to time as necessary.

The relative arrangement of the parts of 55 the complete furnace and the manner of supporting the several parts may be considerably varied. As shown in Fig. 1 the furnace is supported upon standards *V* directly carrying the chute *L*. The casting or ring *M* is 60 supported directly upon the flanged upper end of the chute *L* and in turn carries a section *W* of the furnace proper which carries the holder *X* for the upper electrode. An upper section *Y* is added, carrying chutes or 65 spouts *Z* through which the material is fed,

a stack *a* for the discharge of the gases generated, and a stoking door *b*.

In commencing the operation of the furnace a block of iron or other suitable material of the shape of the pig *F* is bolted or otherwise fastened to the conveyer with its upper end near the carbon *A* as close to it as possible. The arc being established and the material *D* being fed in, a pool of liquid carbid is formed. Then as the reduction 70 proceeds the operator turns the hand wheel *T* to move the conveyer down together with the pig. When the resistance becomes too high the hand wheel *T* is stopped or turned more slowly. When the resistance becomes 80 too low the hand wheel is turned more rapidly. The product *F* passes downward and projects out of the end of the chute *L* where it is broken off in pieces of suitable size, the material *D* surrounding the pig being carried 85 back to the reservoir and used over again.

The manner of controlling the rapidity of the process by holding up the pig so as to retain the molten material in a die permits of the most efficient utilization of the energy 90 supplied by the current, both as to rapidity of the process and uniformity and high quality of the product; and above all is extremely cheap compared with prior processes by reason of the avoidance of a practically useless 95 crust around the pig of product. By reason of the current's traveling through only the upper molten part of the pig in passing from one electrode to the other I avoid the loss of energy occasioned in previous single-arc furnaces by the necessity of passing the current through the complete length of pig and maintaining the same substantially liquid; thus securing an output quite as great as in a 100 double-arc furnace. At the same time I am 105 enabled to operate with a single arc and thus secure a product of uniformly good quality throughout the cross-section of the pig; a thing which is impossible with a double arc because of the localization of the highest heat 110 at points immediately below the two arcs.

The forming of the die of separate carbons *B* permits of maintaining the die of a uniform size as the carbons wear or are burned off at their inner ends. The amount of 115 shortening of the carbons is compensated for by forcing the carbons inward as they wear so that they constantly touch each other or approximately so to form the die. The upper electrode *A* may also be made adjustable 120 in any suitable manner.

It is not essential to the process that the pig as it emerges from the die shall be surrounded by the material *D* or any other non-conducting material. The withdrawal of 125 the pig may of course be accomplished by constantly-driven or automatic mechanism instead of the hand mechanism shown, and such constantly-driven mechanism may be controlled by hand or automatically. The 130

specific form of conveyer shown is not essential to success, a great variety of conveyers being adapted to the same purpose.

A furnace differing in some respects from that shown in Fig. 1, though embodying the same general principles of operation, is shown in Figs. 3, 4 and 5. The die in this case is formed of carbon plates B, constituting the lower electrode, and lower plates c preferably of graphite, fire brick or other material (conductive or not) which will not be injured by exposure to the high heat. The die tapers and is supported in a holder preferably in the form of a casting d supported in turn upon legs or other suitable supports V. The upper electrode A may be arranged with its lower end within the die as in Fig. 6, but is shown in this case as slightly above the die, though not so high as to form the solid pig or any portion of it above the die so as to prevent its being drawn downward. The zone of fusion, or at least the pool of fused material, fills the cross-section of the die so that as the liquid solidifies it may be drawn downward. In order to hasten the solidification of the material before it passes out of the die (which solidification is desirable though not essential) the lower carbon holder d may be provided with a jacket or tubular space e running entirely around it, through which cold water may be passed. Any other suitable means may be utilized for cooling the die or for cooling the pig directly. The pig may be drawn out in a directly vertical line. A suitable means for holding up the pig and lowering it at a desired rate is shown, comprising a table f upon which the pig rests and which may be lowered manually or mechanically. When it has been lowered to expose a desired length of the pig F the latter may be broken off as for example at the point g, and the broken off part removed. Inwardly projecting blades h or equivalent devices hold up the remaining portion of the pig until the table f can be shoved up against its bottom.

The mode of operation of the structure shown in these figures is substantially the same as that of the furnace of Fig. 1.

Fig. 6 illustrates certain additional modifications which may be made without departing from the spirit of the invention. The lower electrode B is a solid carbon block in the form of a die with its aperture of uniform cross-section throughout its length. The upper electrode A may be elevated above the die a slight distance as in Figs. 1 and 3, or as shown it may extend down within the die; the essential point being to avoid placing it high enough above the die to permit the partial solidification of the fused material before it can enter the upper end of the die. The feature of extending the upper electrode down within a lower electrode however is not claimed as my invention. In this figure means

are indicated for regulating the height of the upper carbon A, either for adjusting it for wear or for permitting its gradual movement from the lower part of the die to the upper part in the carrying out of the process. This means may consist of a controlling wheel j the hub of which is screw-threaded and engages a screw-threaded end of a rod k carrying the electrode. For lowering or drawing down the pig F a pair of roughened rollers l may be provided, geared together as shown and one of them carried on a shaft m controlled by any suitable operating device or mechanism, such as the hand-controlled worm shaft m'. The lower electrode in this case is supported in a shell of metal n constituting the principal portion of the wall of the furnace proper, the upper carbon holder k being supported from the top of the furnace as indicated. In every case suitable insulation o is provided between the parts of the furnace carrying the upper and lower electrodes. The wall of the electrode or die B is tapered at its upper end to guide all the material toward the opening of the die.

Fig. 7 shows the application of the principle to a double-arc furnace, that is to say, a furnace in which there is an arc between each of two electrodes and the fused material. The electrodes A and B' may be mounted similarly to the upper electrode of Fig. 6 or in any other suitable way. The die p is composed of bricks of strong heat-resisting material, preferably graphite, and may be supported in a shell n similar to that of Fig. 6. The passage through the die may be of uniform cross-section as shown, or may be tapered as in Figs. 1 to 5. By making the die larger, or arranging the electrodes A and B closer together, they may be lowered into the die. Or they may be arranged as shown a slight distance above the top of the die so that the solid product is formed directly in the die. The withdrawal of the solid pig may be effected by grooved rollers.

In commencing the operation of the furnace shown in Figs. 3 to 7, an iron box or other block of suitable material is arranged with its top so high as to support the molten material in proximity to the upper electrode or electrodes, and is gradually lowered as the pig is formed. It is understood that the arc is formed in the first place in each of the several furnaces by introducing some of the mixture on top of the false bottom and adding broken coke or other form of carbon on top of this until it touches the upper electrode, after which the current is turned on and the material is fed in in suitable quantities. The rollers l of Figs. 6 and 7 may be held against the pig with a yielding pressure, or may be rigid as shown. Preferably their turning is controlled by a worm wheel (see Fig. 6) so that they are automatically locked in any position to which they are moved. Likewise

a worm wheel or equivalent locking mechanism should be used to control the movement of the table of Figs. 3 and 4. The length of the dies will vary with the material to be formed. With a product which solidifies at a very high temperature a solid pig will be formed a short distance below the upper electrode, and for this product a comparatively short die such as is shown in Fig. 1 will be sufficient. For a product which solidifies at a lower temperature or more slowly the die will be longer, and it may even be necessary to apply special cooling means such as described for insuring that it shall be sufficiently hard to be handled in a pig when it emerges from the die. It may of course be slightly plastic so that as it emerges it spreads out laterally to a slight extent, and for the most efficient carrying out of the process it should be sufficiently stiff to be held up and in turn to hold up the fused material above it. It should have a solidified shell capable of retaining the hotter and still liquid material in the center at the time that it emerges from the die, and the point at which the end of the pig is broken off should be sufficiently far away from the die to permit of the solidification of the material throughout its cross-section.

30 The differences in detail presented by the several different forms of the invention shown are in general interchangeable. That is to say, a furnace may be built comprising any desired features selected from each of the several furnaces described.

In previous ingot furnaces the lime and carbon had to be very finely ground so that the molten lime should not percolate too freely into the material outside of the zone of fusion and thus form a pig of irregular quality and with a thick crust. With my improved apparatus in which all the material passes through the zone of fusion and is reduced therein, the former expense for fine grinding is not necessary. Also in previous ingot furnaces it has been found impracticable to use limestone, the crust formed in such a case being very hard as compared with that obtained by the use of lime. With my improved apparatus producing a crustless pig, limestone may be substituted for lime with a considerable saving in expense.

Though I have described with great particularity of detail certain embodiments of my invention, yet it is not to be understood that the invention is limited to the particular embodiments described. Various modifications thereof in detail and in the arrangement and combination of the parts may be made by those skilled in the art without departure from the invention.

What I claim is:—

1. In an electric furnace for the production of calcium carbide or the like, means for maintaining a zone of fusion, refractory walls

closely circumscribing such zone, and means for progressively passing all the material to be utilized in forming the product within said walls and through said zone of fusion and discharging it in solidified form, said means engaging the solidified product, whereby is obtained a pig devoid of crust. 70

2. In an electric furnace for the production of calcium carbide or the like, means for maintaining a zone of fusion in which the material is fused, a die having walls closely circumscribing such zone, and means for withdrawing the material from said die progressively as it solidifies and thus holding up the fused material within said die. 75

3. In an electric furnace for the production of calcium carbide or the like, means for fusing the material, and a die through which the fused material passes and by which it is shaped, and which separates the unreduced material above from the reduced material beneath, and means for withdrawing the material from said die progressively as it solidifies and thus holding up the fused material within said die. 80

4. An electric furnace having a die through which the material passes, means for fusing the material within such die, said die adapted to retain the product until it is sufficiently solidified to emerge in a solid pig, and means for controlling the rate of emergence of said pig. 95

5. An electric furnace having a die through which the material passes, said die formed of refractory conducting material and serving as one of the electrodes, a second electrode arranged adjacent thereto whereby when a suitable current passes between them the material within the die is fused and reduced, and means for controlling the passage of material through the die adapted to retain the product therein until it is sufficiently solidified to emerge in a solid pig. 100

6. An electric furnace having a die composed of sections of carbon forming an electrode, said sections being adapted for radial adjustment. 110

7. An electric furnace having a die through which the material passes, means for fusing the material within the upper portion of such die, said die prolonged sufficiently below the zone of such fusion to permit the fused product to sufficiently solidify within the die to emerge therefrom in a solid pig, and the die flared at its discharge end to facilitate the 115 emergence of such pig.

8. An electric furnace having a die through which the material passes, means for fusing the material within the upper portion of such die, and means for cooling the lower portion of such die, whereby the molten product is sufficiently solidified within the die to emerge therefrom in a solid pig. 125

9. An electric furnace having a die, means for fusing all the material which passes 130

through said die, a chute on the discharge side of the die, and means for feeding between the chute and the solidified product emerging from said die a quantity of granular material.

10. An electric furnace having a die, means for passing a portion of the material through said die and fusing the same, and means for passing a portion of the material outside of said die and about the solidified product emerging from the die.

11. An electric furnace having a fixed curved chute, and means for conveying the reduced material in a curved pig through said chute.

In witness whereof, I have hereunto signed my name in the presence of two subscribing witnesses.

JESSE CRITZ KING.
